PUSH BAR

Ernest R. Erickson, Des Moines, Iowa, assignor
to C. E. Erickson Company, Incorporated, Des
Moines, Iowa, a corporation of Iowa

Application December 11, 1939, Serial No. 308,729

5 Claims. (Cl. 16—1)

My invention has reference to that class of devices used by attachment to the stiles of a door to form a horizontal cross member by which the door can conveniently be pushed open.

5 An object of my invention is to provide a push bar of the type above referred to which can be readily adapted to doors of various widths.

Another object is to provide a construction in which the principal structural elements are particularly adapted for carrying an advertising or sales promotion message, or other printed or decorative matter.

In view of the last mentioned object, a further object is to provide a construction in which the principal structural elements above mentioned can be readily interchanged.

Another object is to provide a bar constructed with end extension elements in which the assembly shall be firm and rigid and in which the parts can be maintained in assembled relation by a minimum number of bolts.

With these and other objects in view, my invention consists in the construction, arrangement and combination of the various parts of my device, whereby the objects contemplated are attained, as hereinafter more fully set forth, pointed out in my claims and illustrated in the accompanying drawing. Although the invention is susceptible of a variety of embodiments, it is necessary to fully describe and illustrate more than one in order to give a full understanding of the invention both from its structural and functional standpoints. Accordingly, I have illustrated a preferred and desirable embodiment of the invention in the accompanying drawing, in which:

Figure 1 is a perspective view of a door with a push bar embodying my invention represented as attached to the door.

40 Figure 2 is a top plan view of my device, a part of the figure being in horizontal section.

Figure 3 is a view, partly in vertical section, taken on the line 3—3 of Figure 2.

45 Figure 4 is an enlarged vertical sectional view taken on the line 4—4 of Figure 3; and

Figure 5 is an enlarged vertical sectional view taken on the line 5—5 of Figure 3.

In the accompanying drawing I have used the reference numeral 10 to indicate generally a door of the type with which my device is commonly used. The door 10 has vertical stiles 12 and 14 to which my push bar is attached by screws 16. Such an installation is commonly made on the doors of grocery stores and markets, both to provide attractive ornamentation

therefor and to protect the glass from finger-marks, etc.

It has become a practice among bakeries and other wholesale purveyors of foodstuffs to furnish door pushes of this type to grocery stores, 5 and advertising or sales promotion message with relation to certain food products being displayed on the bar or attached thereto. Obviously, such a device must incorporate some arrangement whereby it can be adapted to doors of various 10 widths.

Furthermore, in view of the fact that the back side of the push bar can be viewed through the glass in the door, or through the screen wire, when the bar is used on a screen door, it is desirable to place a message or decoration on that side of the bar as well as on the more exposed side. In case the two messages are not the same, it may be desirable to locate one of them on the back or front of the bar according to 20 whether the bar will face the inside of the store or toward the outside. For example, the message "Thanks! Call Again!" should be faced so that it is read by a customer going out through the door upon leaving the store. If the 25 push bar is located on the inside of a screen door, then the message above quoted should be located on the side of the bar away from the screen. On the other hand, if the bar is to be affixed to the outside of the glass door, then the quoted message should be on the side of the bar next to the glass. Therefore it is desirable to have a construction wherein the desired message can be conveniently mounted on either side of the bar, or whereby a desired combination 30 of messages can be assembled to make up a bar. 35

In the detailed views showing my push bar, the numerals 18 and 20 indicate generally a pair of plates, the shape of which is best shown in the cross sectional view of Figure 5. As there 40 shown, plate 20 comprises a flat front portion 22, and beveled edge portions 24, which constitute a flange giving strength and rigidity to the plate. The edges of the beveled portions 24 terminate in inturned flanges 26. The plates 18 45 and 20 are identical as to their cross sectional shape, and, as shown in Figure 5, they are located back to back, the flanges 26 being adjacent. This adjacent relationship is maintained by caps 28 and 30 which engage the ends 50 of the plates 18 and 20 and hold them together.

The assembly thus far described constitutes the central portion of my push bar. It is supported on stiles 12 and 14 by the extension members indicated generally as 32. The latter have 55

a foot portion 34 with perforations 36 to receive the screws 16. Extending at an angle from the foot portion 34, is a portion 38 whereby the bar is spaced away from the door. The portion 38 connects with a longitudinally extending portion 40 which is formed in cross section as shown in Figure 4. The shape therein indicated gives greater strength and rigidity to the member than it would have if it were a flat plate. The portion 40 of the extension members 32 passes through a slot 42 in the caps 28 and 30. At the inner end, the portion 40 is provided at top and bottom edges with hooked ends, the conformation of which is shown in Figures 2, 3 and 5. It will be seen in Figure 5 that along the greater portion of the length of the part 40 of the extension members 32, the outer edges 44 lie along the inside face of the flanges 26 on the plate 18. At the inner end of the part 40 however, the edge 44 is bent as shown at 46 in Figure 2, and is provided with a notch 48 whereby it engages the inturned flanges 26 on the plates 18 and 20. The engagement of the notches 48 with the flanges 26 accomplishes two results. In the first place, it achieves great rigidity of the extension members 32 with respect to the central assembly comprising plates 18 and 20 and the caps 28 and 30. The inner end of the extension members 32 is guided by the coaction of the flanges 26 with the notches 48, and the outer end by the passage through the slots 42 in the caps 28 and 30. A second result is that spreading of the mid portions of the plates 18 and 20 is prevented, because the plates are firmly held together intermediate their ends by the fact that the notches 48 embrace the flanges 26 on both plates 18 and 20.

Adjustment of the push bar to fit doors of various widths is accomplished by sliding the extension members 32 through the caps 28 and 30, and the desired extension is maintained by passage of the bolts 50 through the caps 28 and 30, plates 18 and 20 and suitable holes 52 in the parts 40 of the extension members 32.

The flat portions 22 of the plates 18 and 20 are well adapted for carrying a sales message, which may be applied by lithographing, silk screen process or in any other suitable manner. In actual production, in order to make the costs as low as possible, it is desirable to make up these separate plates in large quantities with various printed matter thereon. A pair of plates having the desired combination of messages can then be conveniently assembled with the caps 28 and 30 and the extension members 32. Inasmuch as the plates 18 and 20 are identical in shape, they may be reversed or interchanged in position so that a desired sales message can be made to face either inwardly or outwardly with respect to the mounting surface. The complete assembly is held in neat and rigid form by only two bolts. A device is thus provided, the parts of which can be economically made up by large production methods, and which can be readily adapted to fill the varying requirements of different applications.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In an extensible push bar, a pair of elongated plates, inwardly directed flanges along the longitudinal edges of said plates, caps engaging the ends of said plates to retain them in position with said flanges in adjacent relation, slots in said caps and extension members passing through said slots, said extension members having notches at their inner ends, said notches embracing the flanges on said plates.
2. In an extensible push bar, a pair of elongated plates, bevelled longitudinal edges on said plates, inwardly directed flanges along said edges, means retaining said plates in position with said flanges in adjacent relation, support members, each having a portion extending between said plates, and notches on said portions of said members, said notches embracing the flanges on said plates.
3. An extensible push bar consisting of a pair of similarly shaped elongated plates, offset longitudinal edges on said plates, inwardly directed flanges along said edges, caps engaging the ends of said plates to retain said plates in relative position with the flanges on one plate adjacent the corresponding flanges on the other, slots in said caps, extension members slidably passing through said slots, said extension members having a pair of notches at their inner ends, each of said notches embracing a pair of said flanges, longitudinally spaced perforations in said extension means, and tie means passing through said plates and through said perforations.
4. In a push bar, a pair of panel members, offset longitudinal edges on said panels, inwardly directed flanges along said edges, means retaining said panels in relative position with the flanges on one panel adjacent the corresponding flanges on the other panel, a support member slidably extending between said panels, and a notch in said support member embracing a pair of said flanges.
5. A push bar consisting of a pair of elongated plates, inwardly directed flanges along the longitudinal edges of said plates, means for clamping said plates in oppositely faced adjacent relation with said flanges together to form a hollow central member, guide means at the ends of said hollow central member, supporting elements passing through said guide means into said hollow central member, and notches on the inner ends of said supporting elements, said notches slidably embracing adjacent pairs of said flanges.

ERNEST R. ERICKSON. 65
